United States Patent Office

Des. 207,041
Patented Feb. 21, 1967

207,041

SHELF

Arthur Goldstein, Scarsdale, N.Y., and Theodore Sobel,
South Orange, N.J., assignors to Butler Industries, Inc.,
Newark, N.J., a corporation of New York

Filed Dec. 20, 1965, Ser. No. 239

Term of patent 14 years

(Cl. D80—9)

FIG. 1

FIG. 2

FIG. 3

FIG. 4

FIG. 5

FIG. 1 is a perspective view of a shelf embodying our new design;

FIG. 2 is an end elevational view thereof;

FIG. 3 is an end elevational view of a modified form of our design;

FIG. 4 is an end elevational view of another modified form of our design; and

FIG. 5 is a perspective view of a modified form of shelf shown in FIGS. 1 and 2 and different therefrom in the addition of a side panel and movable divider panel.

The dominant features of the design reside in the portions shown in full lines it being understood that the center portion of the shelf is shown in broken lines in FIGS. 1 and 5 for convenience of illustration.

We claim:

The ornamental design for a shelf, as shown and described.
